COIN CONTROL FOR ELECTRIC MOTOR OPERATED MACHINES

Filed June 22, 1926

FIG. 1.

FIG. 2.

Inventor:

George W. Werner
By Monroe E. Miller

Attorney.

UNITED STATES PATENT OFFICE.

GEORGE W. WERNER, OF EASTON, PENNSYLVANIA.

COIN CONTROL FOR ELECTRIC MOTOR-OPERATED MACHINES.

Application filed June 28, 1926. Serial No. 117,800.

The present invention relates to coin or check controlled devices for electrical circuits, and aims to provide a novel and improved coin control device for electric motor operated machines, such as, for example, a sound reproducer, which will require the insertion of a coin or token to start the machine and which will permit the machine to operate the intended amount at which time 5 the device opens the motor circuit to prevent further or repeated operation of the machine until another coin is inserted.

The device is intended especially for use on electric motor operated sound reproducers 15 and similar machines provided with automatic switches for opening the motor circuits when the machines have completed their operation, such as, in a sound reproducer, when the record has been played and the finishing end of the sound groove reached. In combination with such a machine it is the function of the present device to establish the circuit of the motor when a coin is inserted and keep the circuit of the motor closed 20 until the intended operation of the machine has been completed, whereby the automatic opening of the motor circuit by the machine itself, will restore the device so that another coin must be inserted to again start the machine, the coin previously inserted being released after the machine is started in operation.

Another object is the provision of such a device which may be constructed or built in 25 a unit separate and distinct from the machine itself, and which may be attached to the machine or used at a distance therefrom.

It is also an object of the invention to provide such a device which is simple in construction and operation.

With the foregoing and other objects in view, which will be apparent as the description proceeds, the invention resides in the construction and arrangement of parts, as 45 hereinafter described and claimed, it being understood that changes can be made within the scope of what is claimed, without departing from the spirit of the invention.

The invention is illustrated in the accompanying drawing, wherein—

Figure 1 is a diagrammatical view of the device as used in combination with an electric motor operated sound reproducer.

Fig. 2 is a section on the line 2—2 of 55 Fig. 1.

As shown in the drawing the control device is used in combination with a sound reproducer having an electric motor 7 for rotating the sound record 8 over which the sound arm 9 moves when the record is played, and these machines, as well known, are generally equipped with an automatic switch 10 in the circuit of the motor to be opened by a finger or portion 11 carried by the arm 9, when the needle of the sound box reaches the inner end of the sound groove, in order to automatically stop the machine. The circuit of the motor is indicated at 12, having the terminals 13 which may be connected by a plug and socket with the wires of an ordinary electric current supply system, using either alternating or direct current. The motor 7 and switch 10 are connected in series.

The sound reproducer is illustrated as typical, it being understood that the control device may be used for other machines operated by an electric motor and having an automatic switch or circuit breaker for stopping the machine when it has completed a predetermined operation.

The device includes a coin chute 14 down which a coin 15 may drop when inserted into the chute, and the device may have any well known or suitable means for rejecting spurious or improper coins, slugs, and the like. 55 The insertion of the coin 15 will establish the motor circuit, with the coin in said circuit. Thus, two pins or contacts 16 and 17 are disposed within the chute to be bridged by the coin 15, as seen in Fig. 2, for closing the motor circuit, as will presently appear.

An electromagnet 18, which may be for either alternating or direct current, controls the pin or contact 17, which is a rod or stem 95 slidable in guides 22 and 23 and having an armature 21 thereon within the field of the electromagnet 18, whereby the magnet being energized will attract the armature 21 to retract or withdraw the contact 17 from the chute 14, to let the coin drop down into a suitable receiver or receptacle. The magnet 18 is connected in series in the circuit 12 with the switch 10 and motor 7, and branches 19 and 20 of the circuit are connected with the contacts 17 and 16, respectively, to connect 100 said contacts in series with the electromagnet, switch 10 and motor 7, whereby the coin 15 in bridging the contacts 16 and 17 will close the circuit and thereby start the motor 7, as well as energizing the magnet 18. Con- 105 110

tacts 24 and 25 are connected in parallel with the contacts 16 and 17 by the respective branches 26 and 27 of the circuit, and are normally open, said contacts 24 and 25 being brought together when the armature 21 is attracted to the magnet 18. Thus, the contact 25 is carried by and insulated from a collar or arm 28 secured on the stem or contact 17, and a spring 29 is provided, between the 10 guide 22 and collar 28 as shown, for moving the contact 17 into the chute 14 and retracting the armature 21 away from the magnet 18.

In operation, when a coin is inserted in the 15 chute 14 and bridges the contacts 16 and 17, this closes the motor circuit, as will be apparent, the current flowing through the motor 7, switch 10, magnet 18 and contacts 16, 17, whereby the machine will operate. The 20 energization of the magnet 18 will attract the armature 21, thereby retracting the contact 17 from the chute 14, so that the coin 15 is released and will drop down the chute into the receiver. The movement of the 25 armature 21 will bring the contact 25 against the contact 24, thereby closing the circuit through the contacts 24 and 25 when the circuit is broken between the contacts 16 and 17 by the release of the coin. This establishes a stick circuit through the motor 7, 30 switch 10, magnet 18 and contacts 24, 25, whereby said circuit is maintained as long as it is not interrupted at any point, inasmuch as the spring 29 will restore the contact 17 and remove the contact 25 from the contact 24 should the circuit be interrupted. Therefore, the machine may complete its 35 operation, and when such operation has been completed, the automatic switch 10 being opened, will break the circuit, thereby de-energizing the magnet 18 and releasing the contact 17 so that the spring 29 restores said contact and removes the contact 25 from the contact 24, and preventing further 40 operation of the machine until another coin is inserted. It is apparent that the switch 10 must be closed before the machine is started.

The device being simple in construction 50 may be constructed in a compact unit, which may be attached to the machine, or the device may be located at a distance from the machine, it being noted that the device may be connected in the circuit of the motor at 55 any suitable point without having to be assembled with the machine.

Having thus described the invention, what is claimed as new is:—

1. An electric circuit controller having 60 contacts to be bridged by the insertion of

a coin for closing the circuit, one of said contacts being movable, and means operable by such closing of the circuit for thereafter keeping the circuit closed as a stick circuit and for moving said contact to release the 65 coin.

2. An electric circuit controller comprising in combination with an electric circuit, an electromagnet in said circuit, a coin chute, contacts in said chute to be bridged by a 70 coin, one contact being movable and being controlled by said electromagnet to be retracted for releasing the coin when the electromagnet is energized, said contacts being in said circuit in series with the electromagnet, and circuit closing means in said circuit in series with the electromagnet and in parallel with said contacts to keep the circuit closed while the electromagnet is energized. 75

3. An electric circuit controller comprising in combination with an electric circuit, an electromagnet in said circuit, a coin chute, a movable contact in said circuit in series with the electromagnet arranged for the closing of said circuit by the engagement of 80 a coin in said chute with said contact, said contact being under the control of said electromagnet to be retracted when the electromagnet is energized so as to release the coin, and means for maintaining the circuit 85 closed, as a stick circuit, while the electromagnet is energized.

4. An electrical circuit having stick means for opening the circuit when the circuit is broken, and means arranged to close said 90 stick means by the insertion of a coin and then to retain the coin until the stick means is closed and to immediately release the coin.

5. An electric circuit including an electromagnet and means controlled by the electromagnet to keep the circuit closed as a 100 stick circuit, and means arranged to energize said electromagnet by the insertion of a coin and to retain the coin until the electromagnet is energized and to then immediately 105 release the coin.

6. An electric circuit including an electromagnet and stick means controlled by the electromagnet to open the circuit when the circuit is broken at another point, and contact means under the influence of the electromagnet connected in circuit with the electromagnet for completing the circuit of the electromagnet by the insertion of a coin and operable to retain the coin until the electromagnet is energized and to then immediately 110 release the coin.

In testimony whereof I hereunto affix my signature.

GEORGE W. WERNER.
